ATTORNEY.

UNITED STATES PATENT OFFICE.

JONATHAN R. FREEZE, OF MIDDLETOWN, OHIO, ASSIGNOR TO RUDD HARDESTY, TRUSTEE, OF DENVER, COLORADO.

RIVETING MACHINE.

Application filed February 1, 1922. Serial No. 533,356.

To all whom it may concern:

Be it known that I, JONATHAN R. FREEZE, a citizen of the United States, residing at Middletown, in the county of Butler and State of Ohio, have invented certain new and useful Improvements in Riveting Machines, of which the following is a specification.

My invention relates to riveting machines and more particularly to machines for riveting together the lapping edge portions of metal pipes of the kind used in drainage and irrigation systems.

It is an object of my invention to provide a power-driven mechanism of simple and practical construction which by a series of periodically recurring movements in a cyclic operation, automatically fastens the lapping portions of a pipe-section together by one or more rows of equidistantly spaced rivets.

Another object of my invention is to provide in a machine of the above described character, a contrivance of novel construction which in the operation of the machine, feeds rivets obtained from a suitable magazine, singly and at regular intervals to holes in the parts to be fastened together.

A further object of the invention is to provide a convenient and efficient means to automatically advance the work at regular predetermined intervals whereby to space the rivets at equal distances along the length thereof, and still other objects reside in details of construction and novel arrangements of co-operating elements, all of which will fully appear in the following description taken in connection with the accompanying drawings in which an embodiment of my invention has been illustrated in simple and practical form.

I desire it understood that although the machine as shown and hereinafter described is particularly adapted for riveting the seams of metal pipe sections, its construction is not limited to this use, since other articles of manufacture which in their formation, require this method of fastening their parts, may be subjected to the cycle of operations of the machine, either in its present form or with such slight modifications of its construction as fall well within the scope of my invention as defined in the hereunto appended claims.

It should be further understood that while I have shown and described the co-operatively associated elements of the machine in the simplest and most practical form at present known to me, variations in their arrangement and individual construction may be resorted to within the spirit of my invention.

In the drawings in the several views of which like parts are similarly designated:

Figures 1^A and 1^B represent, conjointly, a side elevation of the riveting machine;

Figure 2, an end view of the machine looking in the direction of the arrow C, Figure 1^A and drawn to an enlarged scale;

Figure 3, an enlarged section on the line 3—3, Figure 1^A;

Figure 4, a section taken on the line 4—4, Figure 3;

Figure 5, a plan view of the head end of the mandrel of the machine, looking in the direction of the arrow placed across the line 5—5 in Figure 1^A, and drawn to a relatively larger scale;

Figure 6, a longitudinal section along the line 6—6, Figure 5;

Figure 7, an enlarged fragmentary section on the line 7—7, Figure 5;

Figure 8, a transverse section on the line 8—8, Figure 5;

Figure 9, a similar section taken on the line 9—9, Figure 5;

Figure 10, a section on the line 10—10, Figure 5;

Figure 11, a section similar to that of Figure 7 showing the jaws at the end of the rivet feed tube in the position they assume for the passage of the rivet to a hole of the work;

Figure 12, an enlarged sectional elevation of the rivet feed mechanism at the feed-end of the machine;

Figure 13, an enlarged section on the line 13—13, Figure 1^B, corresponding with the line 13—13 in Figure 12;

Figure 14, a section taken on the line 14—14, Figure 12;

Figure 15, a section on the line 15—15, Figure 12;

Figure 16, a fragmentary side view of one of the stripping blades at the entrance to the rivet chute of the feed mechanism, looking in the direction of the arrow D, Figure 13;

- Figure 17, an enlarged sectional elevation of the timing element of the feed mechanism taken on the line 17—17, Figure 12;
- 5 Figure 18, a section on the line 18—18, Figure 17;
- Figure 19, a section taken on the line 19—19, Figure 17;
- 10 Figure 20, a section on the line 20—20, Figure 17;
- 15 Figure 21, a section on the line 21—21, Figure 18;
- Figure 22, a sectional view of the lower portion of the riveting and punching tool taken on the line 22—22, Figure 3, drawn to an enlarged scale;
- 20 Figure 23, a section on the line 23—23, Figure 22;
- Figure 24, a side elevation of the cut-off valve of the feed mechanism;
- 25 Figure 25, an end-view of the same looking in the direction of the arrow E, Figure 24;
- Figure 26, a perspective view of an end portion of a pipe riveted by the operation of the machine;
- 30 Figure 27, a sectional elevation of the feed end of the machine, showing a mechanical means for feeding the rivets to the riveting head at the end of the mandrel, this being a modification of the air-feed shown in the other views;
- 35 Figure 28, a cross-section on the line 28—28, Figure 27;
- Figure 29, a similar section taken on the line 29—29, Figure 27 and Figure 30, an enlarged sectional elevation of the valve which automatically controls the supply of air in the operation of the machine, and the mechanism which operates the valve.
- 40 Referring more specifically to the drawings, the reference character 2 designates the base frame of the machine, which in the construction shown consists of two or more of interconnected I beams.
- The machine comprises three distinctive mechanisms with their respective supports and actuating devices, and the connections required for their systematic operation at determinate periods in a cyclic movement.
- 45 The mechanisms referred to are, first: a punching and riveting mechanism which at the head-end of the machine, punches holes into the overlapping portions of a pipe section supported on a subjacent mandrel, and upsets the ends of rivets entered into the holes by a feed mechanism; second: a spacing mechanism which by intermittent longitudinal movements of the pipe section during the intervals between the operative movements of the riveting and punching mechanism and the feed mechanism, mechanically sets the rivets at predetermined distances; and third: the rivet feed mechanism which after the holes have been punched and prior to the advancing move-
- 50 ment of the pipe, automatically projects rivets into the holes in each cyclic operation of the machine.
- 55 Before proceeding with a detailed description of the co-operating mechanisms of the machine, attention is called to the fact that the construction shown in the drawings is designed for connecting the lapping portions of the pipe by two rows of rivets arranged in staggered relation to each other as illustrated in Figure 26 of the drawings.
- 60 This method of riveting the pipes obviously requires duplex means for punching the holes, feeding the rivets thereto and clinching the ends of the rivets, and inasmuch as in the present construction, said means are exact duplicates and are independent of each other except for their synchronous actuation by one and the same operating mechanism, the description of one of said means in each mechanism will suffice to convey a clear and complete understanding of the construction and operation of the entire machine.
- 65 The riveting and punching mechanism and the feed mechanism are mounted upon the base frame of the machine at opposite ends of a horizontally disposed mandrel which functions as a support for the pipe section and which contains the conduit or conduits through which the rivets, periodically supplied by the feed-mechanism, pass to the holes formed in the pipe by the operation of the punching tool.
- 70 The mandrel, designated in the drawings by the reference character 3, is supported upon standards 4 erected on the base frame at the feed end of the machine and upon a vertically adjustable chair or rest 5 at the head-end of the same.
- 75 The riveting and punching mechanism is mounted upon a standard 6 erected on the base frame at the head end of the machine and including a laterally projecting basal portion for the support of the before mentioned adjustable rest, and an overhanging arm on which the punching and riveting head of the mechanism is mounted for vertical reciprocation.
- 80 The feed mechanism is, in its entirety, mounted upon a rearwardly projecting frame 7 which is rigidly fastened at the upper ends of the before mentioned standards at the rear end of the base frame 2.
- 85 Removably mounted at the free end of the mandrel between the overhanging arm of the standard 6 and the chair 5, is a head 8 which as best shown in Figures 5 and 6, supports the pipe section to be operated upon by the riveting and punching tools.
- 90 To clearly illustrate the operations of the different mechanisms embodied in the machine, upon the lapping portions of the metal pipe, the latter has been shown in its

relative position in several of the views and has in each instance been designated by the reference letter W.

The head 8 consists of a block 9 provided 5 with a circular shank 10 for its insertion in the end of the hollow mandrel, and a shell 12 in which the block is fitted. The shell has a tapering end portion which facilitates the placement of the pipe upon the mandrel 10 and which is preferably provided with openings for the application of a tool to facilitate the withdrawal of the head from the mandrel. A bolt 13 fastens the block and its shell against relative displacement.

15 The shell has at its sides, parallel flanges 14 which are apertured for the sliding support of pairs of rods 15 upon which are mounted the forming and sizing rollers 16. The upper and lower faces of the shell are 20 concentrically circular to fit within the pipe section and the rollers are relatively positioned to engage the inner surface of the pipe at the sides thereof and thereby co-operate with said faces in holding the pipe in 25 true cylindrical form while its lapping edges are being riveted together.

The purpose of slidably supporting the rods with which the rollers are connected is to permit of a forward movement of the 30 latter when the carriage to which the pipe section is connected, reaches the end of its forward travel, and thereby allow of the application of rivets at the extreme end of the pipe, as will hereinafter be more fully described.

The block of the head has in its upper surface, a series of recesses which are adapted to hold anvils 17 for the support of the rivets while their ends are being upset, 40 to provide passages 18 for the slugs punched out of the metal by the action of the punching tools, and to contain the rivet guiding and placing members at the ends of the feed conduits, which in the operation of the machine, function to direct the rivets into the 45 holes of the pipe.

The anvils 17 consists of cylindrical blocks which are fitted in the correspondingly shaped recesses of the mandrel head adjacent the forward end thereof, the recesses 50 18 at the opposite end of the head constitute wells which receive the slugs punched out of the metal in forming the rivet holes, and are continued into slanting passages 19 that 55 open as at 19^a in the sides of the shell 12 for the discharge of the slugs outside the head, and the recesses which hold the rivet guiding and placing members of the feed mechanism, are formed intermediate of the 60 other recesses at the ends of partially curved channels 20 which are continued to the end of the shank 10 of the head, and connect with conduits 21 which extend longitudinally through the hollow mandrel, to the timing element of the feed mechanism at the rear-

ward end thereof, as will hereinafter be more fully described.

The rivet guiding members hereinbefore referred to, each consist, as best shown in Figures 7 and 11 of the drawings, of a pair 70 of jaws 25 preferably pivotally mounted upon a support 23 which is fastened in the respective recess of the mandrel head by means of machine bolts 24. The jaws 25 meet centrally above the channel 20, and they are 75 inferiorly tapered to spread apart as shown in Figure 11, by the impact of a rivet forcibly projected through the channel in the operation of the feed mechanism. Coiled springs 27 placed in recesses of the support 80 23 beneath tail pieces at the lower ends of the jaws, serve to yielding hold said members in their normal position shown in Figure 7.

The jaws function in the operation to direct the rivets into the holes of the lapping 85 portions of a pipe supported on the mandrel, and after the rivets, which in the drawings have been designated by the letter R, have passed beyond the jaws and the latter have reassumed their normal position, they are 90 supported on the heads thereof until the pipe in which they are inserted, is advanced to the position in which the rivets rest upon the anvils, as will hereinafter be described.

The punching and riveting mechanism of the machine comprises a plunger head 28 which is fitted for vertical reciprocation in a slideway of the overhanging arm of the standard 6. The head, as shown in Figures 5, 22 and 23, is hollow and it carries at its 100 lower end a stock 29 which holds the riveting hammers 30 and the punches 31 of the mechanism.

The stock has a flange which rests upon a shoulder at the lower end of the plunger-head and it is secured by means of a gag 32 and a wedge key 33, the latter of which is tightened by nuts 34 on a threaded stud 35 which extends from a side of the head 28 through an opening in its end.

The tools 30 and 31 are of cylindrical form and have at the ends of their shanks beveled heads by means of which they are suspended in correspondingly formed openings of an assembling plate 36 which is fastened at the lower end of the tool stock by a flange nut 37. The plate is held against rotation by a tenon, which is fitted in a correspondingly formed groove in the adjoining surface of the stock.

It will be apparent that the above described method of fastening the tools to the reciprocating head permits of their ready removal and replacement in case of wear or breakage.

The head 28 is reciprocated in the operation of the machine, through the instrumentality of an eccentric 38 on a shaft 42 which extends transversely to the direction of its reciprocating movement. The eccentric is

105
110
115
120
125
130

disposed inside the hollow head and gives motion to a loosely surrounding ring 39, the downwardly extending stem 40 of which, terminates in a spherical knob 41. The eccentric ring engages with a bearing block 43 at the upper end of the head in which it has its movement, and the knob at the end of its stem bears in a correspondingly formed depression of a wear block 44 at the lower end of the head.

The rotary movement of the shaft is through the medium of the eccentric converted into a linear reciprocating movement of the head which causes the tools at the lower end thereof, to intermittently engage with the pipe section supported on the mandrel, it being understood that the hammers and the punches of the head are alined respectively with the anvils 17 and the wells 18 of the head at the end of the mandrel.

A wedge 45 in the slideway is longitudinally adjustable to take up wear and thereby prevent lateral motion of the head during its reciprocating movement.

25. The shaft 42 which is supported in bearings on the standard 6, is held against longitudinal displacement by collars 46 at its end protruding forward of the arm in which the plunger head has its movement, and a gear wheel 47 loosely mounted on the shaft, meshes with a pinion 48 on a drive shaft 49 which is mounted on brackets of the standard 6 and carries a fly wheel 50.

35. A clutch member 51 slidably mounted on the shaft 42 is adapted to secure the rotative continuity of the gear wheel 47 with the shaft and its positions are controlled through the medium of a hand lever 52 which is fulcrumed on the standard 6 as at 53.

40. A link 54 connects the lever with a bell crank 55 which through the medium of a coiled spring on a connecting rod 56, gives motion to a second bell crank 57. A push rod 58 co-operates with a cam face on the sliding clutch member, to separate it from the gear wheel and a forked bell crank 57 is connected in a circumferential groove of the member to move it in the opposite direction. The push rod has a lever connection 45 with the before mentioned rod 56, to be moved to and from its operative position through the medium of the bell crank 55 and the therewith connected lever 52 which extends forward of the overhanging arm of the standard to be within easy reach of an operator standing at the head end of the machine.

45. A spring-pressed friction brake 59 engaging with said collar at the end of the shaft 42 insures immediate discontinuation of the rotary movement of the shaft when the clutch member is disengaged from the gear wheel 47.

The pipe section W which, as stated hereinbefore, is in the operation of the machine,

intermittently advanced to space the rivets by which its lapping edges are connected, is to this end fastened to a carriage which is mounted to move lengthwise of the mandrel upon two rails 65 arranged at opposite sides thereof. The carriage which, in the drawings, is designated by the reference numeral 60, is composed of a body 61 and two laterally projecting wings 62 which fit inside the end of the pipe section and extend partially beyond the same. Eccentric clamps 63 on the outer portions of the wings, forcibly engage with the outer surface of the pipe to secure it to the carriage.

The pipe section thus fastened fits snugly around the upper and lower bearing surfaces of the head at the end of the mandrel and it is interiorly engaged by the sizing rolls 16 which co-operate with said surfaces to maintain the pipe in true cylindrical form. 85 The pipe at the point at which it engages the head, is supported upon the before mentioned chain or rest 5 which consists of a hollowed seat swivelled at the upper end of a screw 67 which extends into a correspondingly threaded opening in the basal portion of the standard 6.

The rails 65 upon which the sliding carriage is supported are mounted on benches 66 which are fastened to the base frame of the machine and extend transversely beneath the mandrel of the same. Guide ways at opposite sides of the benches serve to slidably support a pair of ratchet bars 68 which in the operation of the machine, function to intermittently advance the carriage and the therewith connected pipe sections a distance equal to the spaces of their teeth.

The equidistantly spaced teeth of the ratchet bars are to this end engaged by 105 gravity pawls 69 mounted at opposite sides of the carriage in engagement with hand levers 70 which provide a convenient means to disengage the pawls from the ratchet bars for the relative adjustment of the carriage. 110

In the operation of the machine, the ratchet bars are intermittently advanced a distance equal to the spaces of their teeth by an eccentric on the shaft 42, the ring of which has an upwardly extending arm 71. 115

A lever 72 fulcrumed as at 73 on top of the standard 6, is at one of its ends connected to the eccentric arm and its opposite end is through the medium of a rod 74, connected with a crank-arm 75 on a rocker shaft 77, which is mounted in bearings 76 on the base frame of the machine. Arms 78 at the ends of the shaft, which extend upwardly and at right angles to the arm 75, are connected with the two ratchet bars 68 by 120 means of links 79.

The extreme rearward position of the carriage to which it is adjusted at the beginning of the operation, is determined by an adjustable stop-collar 80 on the mandrel 3 and 130

its said rearward adjustment is effected through the medium of a winding drum 81 with which it is connected by means of a cable 82. The drum 81 is mounted on a shaft 83 which is supported in bearings on the base frame of the machine and which, by means of a pulley 84, is connected with the same line shaft or other source of power, which imparts motion to the drive shaft 10 49 of the riveting mechanism and to the moving members of the feed mechanism hereinafter to be described.

A sliding clutch 85 engages the pulley to secure or break its rotative continuity with the shaft 83 and a hand lever 86 fulcrumed as at 87, is connected with the clutch to move it to and from its operative position. The cable 82 is at its ends, attached to the carriage and to the drum upon which it winds, and it is trained around a sheave 88 which is mounted on brackets 89 on one of the standards 4 which support the mandrel at the rear end of the structure.

The feed mechanism of the machine, 25 which as stated hereinbefore, is assembled upon a frame 7 projecting rearwardly from the standards 4, comprises a stationary hopper 90 which by means of a partition 91, is divided into two compartments which separately provide the rivets required for the two rows by which thelapping edges of the pipes are fastened together.

The hopper is mounted upon a support 92 which is chambered to house the parts by 35 which the rivets contained in the compartments of the hopper are conducted to the timing element of the mechanism.

The parts above referred to comprise a reciprocating blade 93 which in the duplex 40 construction shown in the drawings, is branched to extend at opposite sides of the partition 91, and which in its lower portion, has a transverse groove 94 for its operative connection with a crank 95 at the end of a shaft 96 mounted in a bearing on the support 92. A gear wheel 97 on the shaft meshes with a pinion 98 on a drive shaft 99 which by means of a belt 100, is connected with the line shaft or other source of energy.

50 The two members of the blade have at their upper edges longitudinal grooves adapted to receive the shanks of the rivets, and their said edges slant so as to bring their grooves in alignment with corresponding grooves or slideways in a rivet chute 101 when the blade is at the end of the upward stroke of its reciprocating motion. The chute 101 is fastened to the support of the hopper and its slideways connect at 55 their lower ends with the timing element of the feed mechanism which causes the rivets to move singly and at regular intervals to the feed conduits 21, which connect with the channels of the mandrel head as hereinbefore described.

At the upper edge of the partition 91 of the hopper, are hinged blades 102 which are normally held in a position in which they slant over the grooved edges of the rivet-carrier 93 by means of springs 103 70 as shown in Figure 16 of the drawing. The yielding blades serve in the operation of the machine, to remove rivets other than those extending in the grooves of the carrier, which were carried upwardly from the mass contained in the hopper, and thereby prevent of their being spilled onto the slideways of the chute and of their possible interference with the operation of the timing element.

The timing element shown in detail in Figures 17 to 22 inclusive, of the drawings, 75 comprises a shaft 106 which is rotatably supported in bearings 104 at the end of the rivet chute and on a standard 107 of the frame 7. The shaft is, in the operation of the machine, intermittently oscillated through the instrumentality of toggle arms 108 and 109, which, by means of a rod 110, are connected with a slotted crank 112 on a shaft 113 rotatably mounted in bearings on the frame. A pinion 114 on the shaft 113 meshes with a sliding rack 115 and this rack is by means of a link 116 connected to move in conjunction with one of the ratchet bars 68.

At the lower end of the rivet chute are chambers 117 into which the rivets passing through its slideways, are discharged singly and at regular intervals through the instrumentality of the timing element. Short conduits 118 connect the chambers 117 with curved passages 105 in a block 119 which is fastened upon the frame 7 and which, in conjunction with the piece in which the conduits are formed, provides a support for the end of the chute.

The passages 105 connect, as shown in Figure 12, with the ends of the conduits 21 extending through the hollow mandrel and they have branches 120 extending rearwardly through the block 119 for their connection with pipes 121 leading from a conveniently located source of air under pressure. The passage of the rivets from the chambers 117 to the pipe 21 is automatically controlled by a rotary valve 122 when in the movement of the toggle, the rivets are fed from the chute to the transfer member of the timing element the valve 122 is closed 110 to prevent the compressed air supplied to the ducts 105 from interfering with the operation. The movement of the valve is effected through the medium of a cam 124 fixed on the rotary toggle shaft and engaging with an arm 123 on the valve. A spring best shown in Figures 24 and 25, connected with the arm holds it in constant engagement with a pin at the end of the cam.

Rotatably mounted on the shaft 106 are 120

the two members 125 and 126 of the timing element which co-operate to feed the rivets passing through the chute, into the chamber 117 communicating with the conduits 21 in the mandrel. The two members are mounted one within the other and they have oppositely extending sleeves inside the bearings 104 in which the element is supported. The sleeves have at their ends segmental slots 133 and 134, best shown in Figures 18 and 20 of the drawings, and the shaft has radially projecting studs 135 and 136, which extend in the respective slots to engage with shoulders at the ends thereof.

15 In the normal position of the members, the stud 135 is engaged by the shoulder of the slot in the inner member 125, rearward thereof with relation to the forward direction of rotation of the shaft 106 as indicated by the arrows in Figures 17, 18 and 20, and the stud 136 engages with the shoulder of the slot in the inner member which is forward thereof with respect to the same movement of the shaft.

25 Oppositely wound torsion springs 127 and 128 coiled around the shaft are at their ends connected with the sleeves of the members 125 and 126 and with collars 129 and 130 which are fixed on the shaft at opposite sides of the bearings 104.

The inner cylindrical member 125 of the timer has pockets 131 which normally connect with the slideways of the chute and which, in the operation of the device, function to carry the rivets singly to the orifices of the chambers 117 through which they pass into the passages 105 of the block 119.

The outer member 126 of the timer, consists of a segmental shell which fits around the inner member, and a sharp-edged blade 132 which in the operation of the timer, moves across the ends of the slideways of the chute to separate the rivets which had passed into the pockets of the inner member, from the others and to hold the rivets in the slideways against downward motion while the inner member carries its load to the point of discharge.

35 In the operation of the timer, the shaft 106 turned in the direction of the arrows through the medium of the toggle movement, causes the spring 127 to unwind while the spring 128, which is coiled in the opposite direction, is tensioned and thereby transmits the movement of the shaft to the cut-off member 126.

45 The member rotates with the shaft until the end of its blade 132 engages with a shoulder on the rivet chute in which position it separates the rivets which previously had entered the pockets of the transfer member 125 from those in the slideways.

55 After the member 126 has thus completed its operative movement, the stud 135 on the shaft contacts with the shoulder in the slot

of the inner member, opposite to that it normally engages, the stud having passed idly through said slot while the outer member had its operative movement.

The engagement of the stud with the shoulder of the slot causes the transfer member 125 to follow the movement of the shaft, until after it has discharged the rivets carried in its pockets into the chambers 117, when the movement of the shaft is reversed 75 and the springs return the members to their original position.

It will be observed that during the continued rotation of the shaft after the member 126 has reached the end of its operative movement, the stud 136 moves idly through the slot 134 and re-engages the shoulder thereof during the opposite movement of the shaft to return the member to its original position.

80 The pipe 121 which connects the conduits 21 in the mandrel with a source of air under pressure, passes over the machine in close proximity to the overhanging arm of the standard 6 where it is within easy reach 85 of the operator.

85 A valve 137, which normally closes the pipe, is adapted to be opened by the upward movement of its downwardly extending stem which is engaged by a push bar 138 slidably mounted on the housing 28 of the plunger head 29. The lower end of the push bar extends in the path of a cam 139 on the shaft 42, which is arranged to lift the same and thereby open the valve at the time that 100 the riveting head, after having engaged with the work on the mandrel, moves upwardly in its reciprocating motion.

A bell crank lever 140, disposed to contact with the valve stem, independent of the push bar, is engaged by the end of a pull rod 141 when it is desired to open the valve by hand, as may be required to dislodge a rivet sticking in one of the passages or conduits through which the rivets move, or to supply a rivet to the work in case the timing element has accidentally failed to deliver the rivets at the regular period in the cyclic operation.

115 Another valve 142 in the pipe 121, at the head end of the machine, is provided to shut off the supply of air when the machine is not in operation. The valve is operated by hand and its lever is by means of a chain or cord 143 connected with a spring-pressed brake-shoe 144 which is pivotally mounted at the lower end of the rivet chute of the feed mechanism.

120 The shoe normally engages with the heads of the lowermost rivets in the slideways 125 to hold them against downward movement and thereby interrupt the supply of rivets to the timing element in case it is desired to discontinue the feeding action while the machine is in operation. When the valve 130

142 is in its closed position, the shoe engages the rivets in the chute and by its weight holds them against downward motion while if the valve is subsequently 5 opened, the pull on the rope or cable 143 by rotation of the valve, raises the shoe and permits the rivets to move downwardly to the timer at the same time that the air is supplied to move the rivets to the forward 10 end of the machine as hereinbefore described.

The feed mechanism illustrated in Figures 27 to 29 inclusive, differs from that hereinabove described, in that it operates 15 without the aid of fluid pressure.

The rivets supplied through the medium of a timing mechanism as in the first described construction, fill the conduits 21 and the passages connected therewith, in a continuous series extending from the point at 20 which they enter to that at which they are inserted in the holes of the pipe on the mandrel.

Pressure exerted upon any one rivet of 25 the series at the feed end of the machine is transmitted through the others to the rivet at the forward end of the feed line, which consequently is pushed past the guiding members 25 into the holes of the pipe section.

The distance between the feed and riveting mechanisms of the machine, at opposite ends of the mandrel, makes it imperative 30 that the series of rivets be impelled at as many intermediate points as may be necessary to prevent of their line being buckled in the conduits.

With this end in view, the feed mechanism includes a number of co-operatively 40 associated propelling members which are arranged at regular intervals inside the mandrel and which operate in conjunction with the timing element, to intermittently engage with the rivets in the conduits 21 and forcibly move them a distance substantially 45 equal to the length of one of them.

The conduits 21 are made in sections connected by interdisposed blocks 148 which provide a support for the propelling means 50 above referred to. The blocks are bored to provide a continuous passage for the rivets in conjunction with the sections of the conduits between which they are disposed and their upper surfaces are recessed to admit 55 the co-operating parts of the mechanism arranged in the upper portion of the mandrel.

Slides 146 supported in the rectangular recess of each block, contiguous to the sides thereof, are engaged by spring blades 158 60 which frictionally restrain their independent movement.

Bell cranks 157 are fulcrumed to and between the slides of each of the several supports disposed in the mandrel, and they 65 conjointly support two bars 147 and 151

which are pivotally connected at the ends of their arms.

The bar 151 which is disposed above the other, is separated therefrom by interposed distance pieces 152 made of rubber or other suitable material and it has at its end, projecting beyond the rear end of the mandrel, a rack 153 which meshes with a pinion 154 on a shaft 155 of the toggle movement of the timer.

The bar 147 carries a number of push heads 146 which extend into longitudinal slots 145 of the conduit 21. The heads which straddle the bar, fit in grooves in the opposite sides thereof and their lower ends are bifurcated as shown in Figure 29, to permit of their straddling the shanks of the rivets in the conduit when by downward movement of the bar 147, they are constrained to enter the conduit through the slots thereof. The heads 146 are held in place on the bar 147 by springs 150 which permit of their yielding displacement in the event of their coming in contact with the edges of the rivet heads as may accidentally occur.

In the operation of the mechanism, the bar 151 is intermittently reciprocated in synchronous operation with the timing element of the automatic feed. The longitudinal movement of the bar is by rotation of the bell cranks about their fulcrums on the slides 156, converted into a downward movement of the bar 147 with the result that the heads 146 are entered between adjoining rivets in the conduit 21, it being understood that the slides are restrained from following the movement of the rack bar by the spring blades 158. When, however, the bar 147 is held against further downward motion by its contact with the conduit 21, the continued longitudinal movement of the rack bar causes the slides to move in conjunction therewith, thereby imparting a longitudinal movement to the bar 147 and to the rivets with which its heads engage.

The entire line of rivets is thus fed a distance equal to the length of one of them with the result that the rivet at the forward end of the line is forcibly inserted into the 115 holes in the lapping portions of the pipe on the mandrel, while another rivet is added to the line at the feed end of the machine by the simultaneous action of the timing element.

Having thus described the construction of the riveting machine in its preferred and modified forms, the cyclic operation of its interrelated elements and mechanisms will be readily understood. The operator standing at the head-end of the machine fastens the end of a pipe-section to be riveted, to the carriage 60 by means of the clamps 63 and after having lifted the pawls 69 to their inoperative position through the medium of 130

the levers 70, causes the carriage to move rearwardly along its rails into engagement with the previously adjusted stop 80, by rotation of the winding drum 21. When the carriage is in this position, the free end of the pipe section rests, with its lapping edges uppermost, upon the head of the mandrel, and the latter is supported upon the vertically adjustable chair 5.

10 With the parts thus positioned, the operator first actuates the reciprocating punching and riveting head by movement of the controlling lever 52, in order to produce the first pair of holes in the lapping portions 15 of the pipe at the extreme end thereof. He subsequently opens the air line by adjustment of the valve 142 and at the same time releases the rows of rivets in the chute of the feed mechanism which were held against 20 downward movement by the frictional engagement of the shoe 144.

During the subsequent upward movement of the punching and riveting head, the reciprocating ratchet-bars 68 cause the 25 carriage and the therewith connected pipe section, to move forwardly a distance equal to the spaces between its teeth, and the rack 115 engaging with the pinion 114, operates the timing element as hereinbefore described, with the result that two rivets are 30 scribed, with the result that two rivets are separately fed into the chambers 117. During the last mentioned operation, the valve 122 is opened by the action of the cam 24 on the rotary toggle shaft, upon its stem 35 123 and the rivets pass from the chambers into the curved channels 105 communicating with the conduits 21. After the valve 122 has subsequently been returned to its closed position, the cam 139 on the rotating 40 shaft 42 opens the valve 137 which admits the pressure fluid supplied to the pipe 121 to the channels. The fluid forcibly projects the rivets through the conduits 21 and past the spreading jaws 25, into the holes 45 previously punched in the lapping ends of the pipe section, which by the forward movement of the carriage were brought in register with the delivery ends of the channels 20.

50 The jaws 25 direct the rivet to move straight into the aligned holes of the pipe, and when closed together by their springs after the rivet head has passed their upper ends, they provide conjointly a support upon which the rivet rests until, by the next forward movement of the carriage, the pipe section is again advanced.

55 After the rivets are placed, the automatic valves in the air line are returned to their closed position, and the punching tools on the descending head, produce a second pair of holes in the pipe section. During the subsequent upward movement of the reciprocating head, the pipe section is again advanced and a pair of rivets is inserted in

the last two holes as before, and the rivets which were placed in the holes by the first operation, are now positioned on the anvils 17 of the mandrel head and beneath the riveting hammers of the reciprocating plunger head which, in the following downward movement of the head, upset the ends thereof.

In the continued operation of the machine, one pair of rivets is clinched, and a pair 75 of holes is punched by each downward movement of the reciprocating head, and the pipe is advanced and a pair of rivets is inserted into the holes produced in the preceding action, during each upward movement of the head, and the lapping portions of the pipe section are thus riveted together along the entire length thereof.

When the carriage to which the pipe is attached, approaches the head at the forward end of the mandrel, it pushes the sizing rolls 16 out of its way by engagement with the sliding rods 15 on which they are mounted and thereby permits of the application of rivets at the very end of the pipe 90 at which it is attached to the carriage by the clamps 63.

It will be understood that the mandrel head and the sizing rolls co-operate to hold the pipe in true cylindrical form during the 95 riveting operation and that in order to adapt the machines for riveting a pipe of different diameter, it is necessary that the head at the end of the mandrel be replaced by one of corresponding size.

The machines may be operated under constant control of the operator by reversing the clutch lever 52 each time a pair 105 of rivets has been stuck in the holes of the pipe, or the operation of the machine may be rendered automatic by fastening the lever in its adjusted position in which the movable clutch member engages its correlative on the gear wheel 47.

In the automatic operation, the pipe is 110 advanced and rivets are fed into the holes thereof alternately with the operative movements of the reciprocating punching and riveting head and the actions are continued in cyclic alternation until the entire pipe 115 has been riveted.

When the operator desires to discontinue the operation, he interrupts the rivet-feed by closing the valve 142, which causes the supply of fluid pressure to be discontinued 120 and whose movement is at the same time instrumental in arresting the passage of the rivets to the timing element, through the medium of the pressure-shoe 144.

If, as may accidentally occur, a rivet becomes lodged in the feed line or the feeding action is otherwise interrupted, a blast of air supplied by manually opening the valve 137 is, in most instances, sufficient to restore the regular order of successive operations,

it being understood that the valve 122 which closes the connections between the chambers of the timing element and the conduits 21 during the intervals between the feeding 5 actions, prevents air from entering the chambers when the valve 137 is opened.

Having thus described my invention, what I desire to secure by Letters Patent is:

1. In a riveting machine, a work-support, 10 a riveting and punching element, an element adapted to feed rivets to holes of work on the support, an element for supplying rivets to the feed element, both the feed element and the supply element being controlled by movement of the first mentioned element, and a spacing element adapted to advance the work alternately with the operations of the other elements.
2. In a riveting machine, a work-support 20 having a passage for rivets to holes in the work, and a pair of pivoted, inwardly tapering rigid jaws at the end of the passage adapted to co-operatively direct into a hole of the work, a rivet passing between them.
3. In a riveting machine, a work-support 25 having a passage for rivets to holes in the work, and a pair of spring-pressed, pivoted jaws at the end of the passage, separable by the passage of a rivet between them and conjointly providing a support for a rivet in a hole of the work, when closed together.
4. In a riveting machine, a tool stock, an assembly plate immovably clamped against an end thereof, and having counter sunk 35 openings, and headed tools in said openings, engaging with said end of the stock.
5. In a pipe riveting machine, a work-support comprising a mandrel having a head provided with concentric bearing surfaces, 40 and rollers on the head co-operating with said surfaces to size a pipe supported on the mandrel, by contact with the inner surface of the pipe.
6. In a pipe riveting machine, a riveting 45 tool, a work-support comprising a mandrel having a head adapted to support a pipe for the operation of the riveting tool, a carriage with means thereon to fasten a pipe, mechanism for propelling the carriage, and sizing rollers movable on the head to advance with the carriage at the termination of its operative movement, whereby to permit of its bringing the end of a pipe at which it is fastened to the carriage, in line 55 with the riveting tool.
7. In a pipe riveting machine, a pipe-supporting mandrel, a carriage having a member to enter a pipe supported on the mandrel, and clamps on the carrier engaging exteriorly of the pipe and co-operating with the member to fasten the pipe to the carriage.
8. In a riveting machine, a normally stationary mandrel, a carriage adapted to ad- 60 vance the work on the mandrel and having 65 means for its attachment to a pipe around the mandrel, propelling mechanism for the carriage, an adjustable stop on the mandrel to limit the return movement of the carriage, and mechanism to move the carriage 70 to engagement with the stop.
9. In a riveting machine, a work-support, a carriage to advance the work on the support, propelling mechanism for the carriage, and power-driven mechanism to effect the 75 return movement of the carriage.
10. In a riveting machine, a work-support, a carriage to advance the work on the support, propelling mechanism for the carriage, a power-driven winding drum to effect the 80 return movement of the carriage, and a cable connecting the carriage with the drum.
11. In a riveting machine, a work-support, 85 a reciprocating riveting tool operative on work on the support, a carriage to advance the work, a reciprocating element to intermittently actuate the carriage, and operating mechanism including means for the reciprocation of the tool, means to reciprocate the element during idle movement of the tool, and an element for feeding rivets to work on the support, operated in conjunction with the carriage actuating element.
12. In a riveting machine, a work-support, 90 a riveting element adapted for operation on work on the support, a container for rivets, an element adapted to automatically transfer rivets from said container, singly and at predetermined intervals to work on the support, mechanism for the 100 conjoint operation of said elements and independent means for controlling the action of the transfer element while the mechanism is in operation.
13. In a riveting machine, a work-support, 95 a riveting element adapted for operation on work on the support, a container for rivets, an element adapted to transfer rivets from said container to work on the support by fluid pressure, a source of fluid 110 pressure connecting with the transfer element, and operating mechanism for the conjoint operation of said elements and means operating in conjunction with said mechanism to automatically open and close said 115 connection at predetermined periods in the operation of the riveting element.
14. In a riveting machine, a work-support, 120 a riveting element, a rivet-feed element including a channel for conveying rivets to the work, and means for feeding rivets singly to the channel, a source of fluid pressure, mechanism for the conjoint operation of said elements, and means operating in conjunction with said mechanism to automatically connect the channel with the source at 125 predetermined periods in the operation of the machine.

15. In a riveting machine, a work-support, a riveting and punching element, an element for feeding single rivets intermittently to work on the support by fluid pressure, a continuously moving driving mechanism and means for the operation of said elements in cyclic succession by the movement of said mechanism. 65
16. In a riveting machine, a rivet-feed element including a container for rivets, a rivet-chute, a lifting member for carrying rivets from the container to the chute, and means operating by movement of the lifting member for removing surplus rivets carried upwardly thereon. 70
17. In a riveting machine, a rivet-feed element including a container for rivets, a rivet-chute, a lifting member for carrying rivets from the container to the chute, and 75
20. a spring-urged wiping blades at the upper portion of the container for removing surplus rivets from the lifting member. 80
18. In a riveting machine, a rivet-feed element including a container for rivets, a lifting member in said container having means for the suspension of rivets by their heads, and a chute having a similar means to receive the rivets discharged from the lifting member. 85
25. 19. In a riveting machine, a work-support having a passage for rivets to the work, a rivet chute, means for feeding rivets thereto, a timing element comprising a carrier-member adapted to receive rivets from the chute and transfer them singly and intermittently to said passage, and a cut-off member adapted hold other rivets in the chute while the carrier member operates, and means for propelling rivets through the passage. 90
30. 20. In a riveting machine, a work-support having a passage for rivets to the work, a rivet chute, means for feeding rivets thereto, a timing element comprising an oscillatory carrier member having a pocket to receive rivets from the chute, and transfer them singly to the passage, and an oscillatory cut-off member periodically obstructing the passage of rivets to the carrier member, and means for propelling rivets through the channel. 100
35. 21. In a rivet-feed mechanism for riveting machines, a rivet-chute, means for feeding rivets thereto, and a timing element comprising an oscillatory carrier member having a pocket to receive rivets from the chute, and an oscillatory cut-off member adapted to periodically obstruct the passage of rivets to the carrier member. 110
40. 22. In a rivet feed mechanism for riveting machines, a rivet-chute, means for feeding rivets thereto, and a timing element comprising an oscillatory shaft, an oscillatory carrier member adapted to receive rivets from the chute, an oscillatory cut-off member adapted to obstruct the passage of rivets to the carrier member, and means for propelling rivets through the channel. 115
45. 23. In a riveting machine, the combination of a work-support having a channel for the passage of rivets to holes in the work, a riveting and punching element operating on the support, a rivet-container, a timing element adapted to transfer rivets one at a time from the container to the channel, a source of fluid pressure, a conduit between said source and the channel, a valve in the conduit, an element to alternately open and close the valve, and mechanism for the operation of said elements in cyclic succession. 120
50. 24. In a riveting machine, a work-support having a channel for the passage of rivets to the work, a rivet chute, means for transferring rivets from the chute to the channel, a source of fluid-pressure, a connection between the source and the channel, a valve in said connection, a brake normally arresting the discharge of rivets from the chute, and means for releasing the brake by movement of the valve to the open position. 125
55. 25. In a riveting machine, the combination of a work-support, a riveting and punching element, an element for feeding rivets to holes in the work, an element for supplying rivets to the feed-element, a spacing element adapted to intermittently advance the work, and mechanism for the operation of said elements in cyclic succession. 130
60. 26. In a riveting machine, the combination of a work-support, a riveting and punching element, an element for feeding rivets to holes in the work, an element for supplying rivets to the feed-element by fluid pressure, a spacing element adapted to intermittently advance the work, and mechanism for the operation of said elements in cyclic succession. 135
65. 27. In a riveting machine, a work-support, means for propelling a rivet to a hole in the work, and adjusting means adapted to automatically align the moving rivet with the hole. 140
70. 28. In a riveting machine, a work-support, means for propelling a rivet to a hole in the work, and readjusting means adapted to automatically align the moving rivet with the hole and to subsequently support the rivet in the hole. 145
75. 29. In a riveting machine, a work-support, a relatively stationary mandrel, a carriage mounted to move lengthwise of the mandrel and having means for its attachment at the end of a pipe around the mandrel, a reciprocating ratchet bar exteriorly 150

of the mandrel, and a gravity pawl on the carriage engaging the teeth of the ratchet bar.

30. In a riveting machine, a work-support, an element for punching holes in a pipe on the support, a container for rivets in arbitrary assemblage, co-operative elements adapted to automatically remove rivets from said container and place them singly and at predetermined intervals in an upright position in the holes of the pipe, and mechanism for the conjoint operation of said elements.

31. In a riveting machine, a pipe-support, an element for punching holes in a pipe on the support, a container for rivets in arbitrary assemblage, co-operative elements adapted to automatically remove rivets from said container and move them singly and at predetermined intervals through the pipe to an upright position in the holes thereof, and mechanism for the conjoint operation of said elements.

32. In a riveting machine, a hollow mandrel for the support of a pipe, an element for punching holes in a pipe on the mandrel, a container for rivets in arbitrary assemblage, co-operative elements adapted to automatically remove rivets from said container and move them singly and at predetermined intervals through the mandrel to an upright position in the holes of the pipe, and mechanism for the conjoint operation of said elements.

33. In a riveting machine, a work-support having a channel for the passage of rivets to the work, a riveting element adapted for operation on work on the support, a magazine for rivets, a source of fluid pressure, a timing element to intermittently transfer rivets singly from the magazine to the channel, an element to intermittently

connect the channel with the source, and mechanism for the conjoint operation of said elements.

34. In a riveting machine, a work support having a channel for the passage of rivets to the work, a riveting element adapted for operation on the work on the support, a magazine for rivets, a source of fluid pressure, a timing element to intermittently transfer rivets singly from the magazine to the channel, an element to intermittently connect the channel with the source, mechanism for the conjoint operation of said elements, and adjusting means actuated by the rivets under fluid pressure to automatically align the rivets with holes in the work.

35. In a riveting machine, a work-support, a reciprocating riveting element, a shaft in operative relation to the element, an element for feeding rivets to the support by fluid pressure, a source of fluid pressure in connection with the feed element, a valve in said connection, and mechanism actuated by rotation of the shaft to alternately open and close the valve.

36. In a riveting machine, a work-support having a channel for the passage of rivets to the work, a rivet-container, a timing element adapted to transfer rivets one at a time from the container, a rivet passage between the timing element and the channel, a source of pressure fluid connected with the passage, a valve controlling the flow of fluid to the channel, and a valve controlling the passage, and mechanism for the operation of the machine, including automatic means to intermittently open each valve alternately with relation to the other.

In testimony whereof I have affixed my signature.

JONATHAN R. FREEZE.
